MARIO S. ROCERETO AND LOUIS D. BERT, OF PITTSBURGH, PENNSYLVANIA.

DISPLAY-RACK.

1,015,079.

Specification of Letters Patent.

Patented Jan. 16, 1912.

Application filed March 14, 1911. Serial No. 614,432.

To all whom it may concern:

Be it known that we, MARIO S. ROCERETO and LOUIS D. BERT, citizens of the United States of America, residing at Pittsburgh, in the county of Allegheny and State of Pennsylvania, have invented certain new and useful Improvements in Display-Racks, of which the following is a specification, reference being had therein to the accompanying drawing.

This invention relates to a display rack, particularly designed for displaying announcement cards, signs and programs.

The primary object of the invention is to provide a rack constructed upon the principle of an easel, whereby the rack can be easily and quickly folded and readily carried in the pocket.

Another object of the invention is to provide a folding rack that can be used for displaying jewelry and various kinds of merchandise, the rack being inexpensive to manufacture and presenting a neat appearance.

25 A further object of the invention is to furnish novel means, in a manner as will be hereinafter set forth, whereby announcement cards and signs can be detachably connected to the rack.

30 With the above and other objects in view the invention resides in the novel construction, combination and arrangement of parts to be hereinafter specifically described and then particularly claimed.

35 Reference will now be had to the drawing, wherein like numerals of reference designate corresponding parts throughout the several views, in which:

Figure 1 is a perspective view of the rack 40 in an open position. Fig. 2 is a front elevation of the same in a closed position. Fig. 3 is an enlarged vertical sectional view of the rack. Fig. 4 is a rear elevation of a portion of cards adapted to be supported by the rack, Fig. 5 is a rear elevation of a modified form of cards, and Fig. 6 is an edge view broken away illustrating one of the hangers as applied to cards.

A rack in accordance with this invention 50 comprises a head 1 and suitably attached to the front side of said head is a center piece 2 having the upper and lower ends thereof projecting above and below the upper and lower edges of the head 1. Pivottally con-

nected to the head 1, at the sides of the piece 2, by pins 3 are legs 4 and 5, said legs having the upper ends thereof beveled, as at 6, whereby the pivoted legs can be swung outwardly. The outward movement of the legs is limited by the beveled end 6 engaging the sides of the center piece 2.

Hinged or otherwise connected, as at 7, to the lower end of the center piece 2 is a center leg 8. The upper hinged end of the leg 8 is provided with a strap 9 that serves two purposes, namely, as a hook and as a stop for limiting the forward movement of the leg 8. Hinged or otherwise connected, as at 10, to the front side of the center leg 8 is a stretcher 11 having the forward end 7c therefore hinged or otherwise connected, as at 12, to a link 13 having the ends thereof pivotally connected, as at 14, to braces 15 pivotally supported, as at 16, by the side legs 4 and 5. The upward movement of the braces 15 is limited by a pin 17, carried by the front side of the leg 4.

The card to be supported at the upper end of the rack is designated 18 and adjacent to the upper edge is provided with a slot 19 80 to receive the hook or strap 9. Pivotally connected to the rear side of the card 18, at the lower edge thereof, are hangers 20, and these hangers are provided with suitable hooks 21 for supporting additional cards 22 85 and 23. The hangers 20 can be swung upwardly upon the rear side of the card 18, and the depending position of said hangers is limited by stop 24, carried by the rear side of the card 18. 90

In Fig. 5 of the drawings there is illustrated a modification of the invention, wherein the rear side of the card 18 is reinforced by a frame 25.

By pushing inwardly upon the said legs 95 4 and 5 the braces 15 shift the link 13 upwardly, thereby causing the stretcher 11 to move the center leg inwardly between the side legs 4 and 5; the structure presenting a compact parcel that can be easily carried 100 in the pocket or in a musician's case. It is in this connection that the rack can be advantageously used by musicians and orchestra leaders supplying music for dances and concerts. The card 18 can contain the name 105 of the orchestra and the remaining cards the name of the dances. The rack in its entirety can be made of light and durable

metal, wood, or any other suitable material, of various sizes and used for various purposes.

What we claim is:—

- 5 A rack comprising a head, a center piece secured to the front side of said head and projecting above and below the same, side legs pivotally connected to said head and having their outward movement limited by
- 10 said center piece, a center leg pivotally connected to the lower end of said center piece and having its upper end provided with a strap for limiting the forward movement of said leg, said strap further constituting a

hook, a stretcher hinged at one end to the front side of said center leg, braces pivotally connected at one end to the side legs, a link pivotally connecting the other ends of said braces together, and means for hinging said stretcher to said link.

20

In testimony whereof we affix our signatures in the presence of two witnesses.

MARIO S. ROCERETO.
LOUIS D. BERT.
